UNITED STATES PATENT OFFICE

156,866

AUTOMOBILE EMBLEM PLATE

Merzellor M. Burnett, South Pittsburg, Tenn.

Application October 8, 1948, Serial No. 149,042

Term of patent 7 years

(Cl. D29—2)

To all whom it may concern:

Be it known that I, Merzellor M. Burnett, a citizen of the United States, residing at South Pittsburg, in the county of Marion and State of Tennessee, have invented a new, original, and ornamental Design for an Automobile Emblem Plate, of which the following is a specification, reference being had to the accompanying drawing, forming part thereof.

I claim:

The ornamental design for an automobile emblem plate, as shown,

MERZELLOR M. BURNETT.
